Term of patent 3½ years

(Cl. D44—5)

Fig. 1.

Fig. 2.

Fig. 3.

To all whom it may concern:

Be it known that I, Nathaniel Hyman, a citizen of the United States, residing at Hewlett, in the county of Nassau and State of New York, have invented a new, original, and ornamental Design for a Butter Dish, of which the following is a specification, reference being had to the accompanying drawing, forming part thereof.

In the drawing:

Fig. 1 is a side elevational view of a butter dish, showing my new design;

Figure 2 is an exploded view in side elevation;

Figure 3 is an end view in elevation;

Figure 4 is a top plan view of the central section;

Figure 5 is a bottom plan view of the central section;

Figure 6 is a top plan view of the bottom section; and Figure 7 is a bottom plan view of the bottom section. The dominant features of my design reside in the portions therein shown in full lines.

I claim:

The ornamental design for a butter dish, substantially as shown and described.
